Primary Examiner—Alan P. Douglas*Assistant Examiner*—Robert M. Spear*Attorney, Agent, or Firm*—Owen J. Meegan; Aubrey C. Brine; Donal B. Tobin**[57] CLAIM**

The ornamental design for actuator turret for gel dispenser, as shown and described.

DESCRIPTION

FIG. 1 is a front elevational view of an actuator turret for a gel dispenser showing my new design;

FIG. 2 is a left side elevational view thereof, the right side elevational view being a mirror image thereof;

FIG. 3 is a rear elevational view thereof;

FIG. 4 is a top plan view thereof; and,

FIG. 5 is a bottom plan view thereof.

The broken line showing a portion of a dispensing canister in FIGS. 1 through 4 is for illustrative purposes only and forms no part of the claimed design.
